UNITED STATES PATENT OFFICE.

CHARLES F. HUMPHREYS, OF LANCASTER, PENNSYLVANIA, ASSIGNOR TO ARMSTRONG-CORK COMPANY, OF PITTSBURGH, PENNSYLVANIA, A CORPORATION OF PENNSYLVANIA.

DESIGN FOR LINOLEUM, OIL-CLOTH, OR FLOOR-COVERING.

45,116.

Specification for Design.

Patented Jan. 6, 1914.

Application filed November 13, 1913. Serial No. 800,867. Term of patent 7 years.

To all whom it may concern:

Be it known that I, CHARLES F. HUMPHREYS, a citizen of the United States, and a resident of Lancaster, in the county of Lancaster and State of Pennsylvania, have invented a new, original, and ornamental Design for Linoleum, Oil-Cloth, or Floor-Coverings, of which the following is a full, clear, and exact description, reference being had to the accompanying drawing, forming part of this specification.

The figure is a plan view of a piece of lineolum embodying my design.

I claim:

The ornamental design for linoleum, oil cloth or floor covering as shown.

CHARLES F. HUMPHREYS.

Witnesses:

ARTHUR BARLOW,
JOHN BARNET.
